UNITED STATES PATENT OFFICE.

BENJAMIN F. MECHLING, JR., OF PHILADELPHIA, PENNSYLVANIA, ASSIGNOR TO THE ALBRO-CLEM ELEVATOR COMPANY, OF PHILADELPHIA, PENNSYLVANIA, A CORPORATION OF PENNSYLVANIA.

ELEVATOR DRIVING MECHANISM.

1,149,206.

Specification of Letters Patent. Patented Aug. 10, 1915.

Application filed May 12, 1914. Serial No. 837,934.

To all whom it may concern:

Be it known that I, BENJAMIN F. MECHLING, Jr., a citizen of the United States, residing in the city of Philadelphia, State of Pennsylvania, have invented a new and useful Elevator Driving Mechanism, of which the following is a specification.

My invention relates to elevator machines such as employed for raising and lowering 10 cars or platforms, generally in vertical shafts, for the transportation of freight or passengers.

My invention resides in elevator apparatus of this character in which great economy in 15 space and cost of manufacture and standardization is procured whereby a single design of the machine will usefully serve for various conditions of elevator service.

My invention resides particularly in a 20 machine of this character for use in a traction system as distinguished from a drum system; and it is part of my invention to provide a traction sheave machine which shall have the advantages above enumerated 25 as to economy in space, manufacture, etc.

By my invention the traction sheave is provided with an integral driving gear driven by pinion which is in turn driven by a worm wheel, the latter driven by a 30 worm coupled to the driving motor. And the arrangement of these driving elements, their bearings, housings, and the main base is such that the economy above referred to is accomplished.

35 My invention resides in apparatus of the character hereinafter described and claimed.

For an illustration of one of the forms my invention may take reference is to be had to the accompanying drawings, in which:

40 Figure 1 is a side elevational view of the complete machine. Fig. 2 is an end elevational view of the same, with the motor removed. Fig. 3 is a cross-sectional view taken on the line X—X of Fig. 1. Fig. 4 is a 45 longitudinal sectional view through the brake wheel and coupling. Fig. 5 is a diagrammatic view illustrating a system of housing and control cables and associated parts. Fig. 6 is a view of the apparatus 50 shown in Fig. 5 taken at right angles to Fig. 5. Fig. 7 is a diagrammatic view of the supply conductors, control switch motor and solenoid.

Referring to the drawings, 1 is a cast

metal bed upon which is secured by bolts 2 55 the electric driving motor M the controlling and reversing switch S for which, having stationary contacts 3 and rotary contacts 4, is housed within the base or bed 1 and accessible through the aperture 5 normally 60 closed by plate 6. The movable contacts 4 are carried by the shaft 7 which extends to the exterior of the bed or base 1 and has secured thereon the control wheel or sheave 8 to which is attached at 9 one end of the 65 control cable 10.

The rotor or armature shaft 11 of the motor M extends into the split coupling comprising the half 12 cast integral with the brake wheel 13, the other half 14 of the 70 coupling being secured by bolts 15 to the part 12, thus coupling the motor shaft 11 to the worm shaft 16 which extends into the bore of the brake wheel 13 and is secured to the latter by key 75 k.

Pivoted to the ear or lug 17 on the bed 1 at 18 is the solenoid 19, having the magnetic jacket or housing 20 and the movable core 21, the latter pivoted at 22 to the lever 23 pivoted at 24 to the yoke or arm 25 on cap 80 38. At its opposite end the beam or lever 23 carries the adjustable weight 26. Pivoted to the lug or ear 27, on the bed plate 1, at 28 and 29 are the ends of brake straps 30 and 31 engaging the brake surface 32 of the 85 brake wheel 13 and terminating at the pivots 33 and 34 on the brake beam or lever 23. Weight 26 tends continually to rotate the beam 23 in a clockwise direction about its pivot 24, as viewed in Fig. 2, thus putting 90 a tension upon the straps 30 and 31 and causing friction at the surface 32 to retard or stop rotation of the shafts 11 and 16 and all parts coupled to or driven by them. And when the solenoid 19 is energized it attracts 95 its core 21 downwardly, thus opposing the weight 26 in its action upon straps 30 and 31, and in effect lifting the brake.

Secured upon the worm shaft 16 is the worm 35, ball thrust bearings 36 being provided for the same within the housing 37 cast integral with the bed plate 1 and having the removable cap 38 bolted to the housing 37. The bearings of the shaft 16 are half within the housing 37 and half within 105 the cap or cover 38 to either side of the thrust bearings 36, these shaft bearings comprising the bearing blocks 40, the latter hav-

ing oil wells 41 within which extend the oil rings 42 loosely embracing the shaft 16 and rotated thereby to lift oil continuously into the bearings. On the right hand end of cap 38, as viewed in Fig. 1, is supported the arm 25 above referred to. Meshing with the worm 35 is the worm wheel 43 secured upon shaft 44 extending through the bearings 45 cast integral with the bed 1 and the housing 37. In the worm gear housing 37 is maintained a supply of lubricant, such as castor oil, in which the worm wheel 43 is continuously immersed to a suitable depth whereby the worm wheel 43 and worm 35 are constantly lubricated.

At the right end of shaft 44, as viewed in Fig. 3, is a pinion 46 which meshes with substantially the lowest part of the internal gear 47 integral with the traction sheave 48 having on its periphery the grooves 49 to receive the traction cable 50, Figs. 5 and 6. The sheave 48 has the hub 51 secured by key k^1 to the shaft 52 which has an outboard bearing 53 carried by the pillar or standard 54 held by bolts 55 to the member 56 of the bed plate 1. The shaft 52 has also an inboard bearing whose lower half 57 is integral with the housing 37 and whose upper half 58 is integral with the cap or cover 38. It will be seen therefore that the housing 37 with its cap or cover 38 provides two bearings for the worm shaft 16, thrust bearings for this worm, and a bearing for the traction sheave. And it will be further noted that the worm gear is disposed beneath the worm and drives the pinion which meshes with the lower part of the internal gear integral with the traction sheave, these features lending themselves to great economy of space, and particularly to the reduction in size of traction sheave machines.

In Figs. 5 and 6 is shown diagrammatically a traction system for elevator car operation. The elevator car 59 has secured thereto one end of the cable 50 which passes over the traction sheave 48 thence over the idler wheel 60, thence again over the sheave 48, and the other end of the cable has secured thereto the counterweight 61. The control cable 10 for the motor control switch S passes through the car 59 and when grasped or held by a person or means on the car 59 can be moved in such direction as to shift the switch S to stop or reverse the motor M. And as seen in Fig. 7 the solenoid 19 is also controlled through the switch S, the arrangement in Fig. 7 being for two-phase alternating current system of which L^1 , L^2 , L^3 , and L^4 are the supply conductors leading to the switch and through the same to the motor M and solenoid 19.

It will be understood that when the motor M is energized, by shifting the switch S by control cable 10, the rotor or armature of the motor will rotate shaft 11 and through

it the shaft 16, worm 35, gear 48, pinion 46, sheave gear 47, sheave 48, cable 50, and car 59 and counterweight 61. And simultaneously with the energization of the motor M, as above explained, the solenoid 19 will be energized, lifting the brake. And when the motor circuit is broken the solenoid will be deenergized and the weight 26 will apply the brake to hold the car in any predetermined or desired position.

75

From the foregoing description it is apparent that I have provided a machine, particularly adaptable to the traction system, whereby a machine of unusually small dimensions may be provided in virtue of the arrangement of the elements of the driving or traction mechanism and their bearings.

80

What I claim is:

1. Elevator driving mechanism comprising a traction sheave, a bed, an outboard bearing for said sheave secured to said bed, an internal gear on said sheave, a housing integral with said bed extending above the same, a worm, worm bearings and a sheave bearing in said housing, a pinion meshing with said internal gear, a worm wheel driving said pinion and driven by said worm, said worm wheel and pinion disposed beneath said worm, and worm driving means disposed upon said bed.

90

2. Elevator driving mechanism comprising a traction sheave, a bed, an outboard bearing for said sheave secured to said bed, an internal gear on said sheave, a housing integral with said bed extending above the same, a worm, worm bearings and a sheave bearing in said housing, said worm and sheave bearings being at substantially the same distance above said base, a pinion meshing with said internal gear, a worm wheel driving said pinion and driven by said worm, said worm wheel and pinion disposed beneath said worm, and worm driving means.

100

3. Elevator driving mechanism comprising a single traction sheave, a bed, an outboard bearing for said sheave secured to said bed, an internal gear on said sheave, a housing integral with said bed extending above the same, a worm having bearings on said housing, an inboard bearing for said sheave on said housing, said sheave bearings extending transversely of said bed and said worm bearings longitudinally of said bed, the axes of rotation of said worm and said sheave being at substantially the same height, a pinion disposed beneath said worm and meshing with said internal gear, a worm wheel meshing with said worm and directly connected to said pinion, and a motor on said bed at the opposite end thereof from said housing for driving said worm.

110

4. Elevator driving mechanism comprising a single traction sheave, a bed, an outboard bearing for said sheave secured to said bed, an internal gear on said sheave, a

120

125

130

housing integral with said bed extending above the same, a worm having bearings on said housing, an inboard bearing for said sheave on said housing, said sheave bearings 5 extending transversely of said bed and said worm bearings longitudinally of said bed, the axes of rotation of said worm and said sheave being at substantially the same height, a pinion disposed beneath said worm 10 and meshing with said internal gear, a worm wheel meshing with said worm and directly connected to said pinion, a motor on said

bed at the opposite end thereof from said housing for driving said worm, said worm disposed within said housing, and said worm 15 wheel rotating within said housing and within said bed.

In testimony whereof I have hereunto affixed my signature in the presence of the two subscribing witnesses.
